UNITED STATES PATENT OFFICE.

AXEL E. SWANSON, OF CHICAGO, ILLINOIS.

BOTTLING-MACHINE.

1,350,249.

Specification of Letters Patent. Patented Aug. 17, 1920.

Application filed January 31, 1919. Serial No. 274,306.

To all whom it may concern:

Be it known that I, AXEL E. SWANSON, a citizen of the United States of America, and a resident of Chicago, county of Cook, and 5 State of Illinois, have invented certain new and useful Improvements in Bottling-Machines, of which the following is a specification.

This invention relates to bottling machines, adapted particularly for varnish and the like, and the main objects of the invention are to provide such a machine of improved form adapted to measure out simultaneously and quickly a number of distinct 15 charges of the filling material ready for subsequent discharge into the bottles to be filled; to accomplish this without exposing the material to the air and without over-drawing and leaving a substantial surplus; 20 to provide for a group or gang of measuring cells arranged uprightly with their open intake ends disposed on a common flood level or filling plane at the top; to provide for each cell a vertically adjustable displacement gage adapted to vary the precise 25 charge as may be required; and to provide for steam jacketing a group of cells such as referred to.

An illustrative embodiment of this invention is shown in the accompanying drawings, in which—

Figure 1 is a top plan of the main body of the machine, namely the part below the line 1—1 of Figs. 2 and 4.

Fig. 2 is a section on the line 2—2 of Fig. 1.

Fig. 3 is a section on the line 3—3 of Fig. 1.

Fig. 4 includes a reduced end view of the 40 device and shows also the automatic float gage.

Fig. 5 is a section through the fan shaped distributing nozzle, at 5—5 on Figs. 2 and 6.

Fig. 6 is a front elevation or edge view of 45 the nozzle shown in Fig. 5.

Fig. 7 is a conventional diagrammatic view of a common mechanism adapted for coactive operation and control of the discharge valves of both the master gage and 50 the unit gages.

In the embodiment here shown the device as a whole comprises mainly a filler frame 1, a source of material including the connecting supply pipe 2, a common meter or 55 master gage 3, communicating with said source, a plurality of small unit gages 4 suc-

cessive to said master gage, a gang funnel 5 adapted and arranged to guide the discharge from said unit gages, a control valve 6 for said source, discharge control means 60 7 for the master gage, discharge control mechanism 8 for said unit gages, a steam jacket 9 for the gages 4, a combined support and guideway 10 below said funnel 5, a removable receptacle or box 11 fitting in said guideway for the bottles or other containers 12 to be filled, a waste trough 13 for the surplus material overflowing from the unit gages, and a spill trough 14 to catch material overflowing from the bottles 12. 70

The several parts are so arranged that upon appropriate manual operation of the controlling means 6, 7 and 8 the liquid material quickly flows, preferably by gravity, from the source of supply to the main gage 75 3 and from there to the gang of individual gages 4, from whence it is permitted to flow downward through the funnels 5 into the ultimate containers 12 wherein it is subsequently transferred to a place for storage, or 80 placed on the market.

The main gage 3 comprises an open-topped cup-shaped reservoir, the bottom of which is provided with an intake aperture, to which is connected the supply pipe 2, and a discharge aperture, to which is connected the pipe 15 leading to the multiple gage manifold 16, the valve 7 being connected in said pipe to control the flow from 85 said main gage. The intake aperture for the gage 3 is provided with a float valve, including a float 17 and the valve proper 6 having an upright stem 19, to which the float is connected, said stem and float having mutually threaded connection, whereby the 90 capacity of the gage may be adjusted, as will be understood. The valve 6 is spherical in shape and fits loosely in a housing 20 inclosing the intake aperture, the top of said housing having a port 21 with the under side of 95 which said valve coats. Stop means 22 are provided to limit the downward movement of the valve sufficiently to prevent closing the upper end of the supply pipe 2. Manual means are provided for controlling said 100 valve 6, said means being in the form of a lever 23 having resilient means 24 urging it upward and having a downwardly projecting hook 25 adapted to engage corresponding upwardly projecting hooks 26 on the 110 top of the float, whereby at the will of the operator the valve 6 may be held closed by

engaging said hooks, and released by disengaging the hooks. Said supply pipe 2 is provided with a downward branch 2' terminating in a drain cock 27 whereby all 5 liquid may be removed from the supply pipe and main gage whenever desired.

The smaller gages 4 are in the form of cups arranged closely together in parallel rows, the tops being rectangular and secured 10 tightly to and substantially integrally with a horizontal frame 28 of plate-like character suitably perforated to receive the gage cups. The walls of each cup are respectively convergent downward from the rectangular top 15 to a centrally perforated circular bottom part.

The feed pipe 15 enters the closed manifold 16 at the back side of the machine by way of a fan shaped distributing nozzle 29 20 having a pair of perforated retarding walls or baffles 31 and 32, illustrated in Figs. 5 and 6, whereby the liquid is spread out or distributed horizontally and caused to flow slowly enough to avoid overflowing into the 25 drain trough 13 before all of the gage cups 4 are filled. Whatever surplus enters the manifold 16 after the cups are filled flows gently over and past the cups into the trough 13 from whence it is discharged through the 30 drain pipe 33 to whatever receptacle (not here shown) may be provided therefor, from whence it may be returned either by a pump or other means to the source of supply.

The valve mechanism for each unit gage 4 35 comprises a spherical valve 35 fitting against the upper side of the port 36 in the base of the cup, said valve being provided with a downward guide stem 37 and an upwardly projecting stem 38 communicating with the 40 manual control mechanism 8 hereinafter described. Each stem 38 is threaded and provided with a vertically adjustable body 39, preferably of downwardly convergent frustum shape and centrally threaded, adapted 45 to vary the volumetric capacity of the gage. By lowering the said body 39 the gage capacity is diminished and by raising same the capacity is increased. Adjustment may be effected by pouring a given volume of 50 liquid into the cup 4 and then lowering the body 39 until the surface of the liquid is raised to the level of plate 28 at the top edge of the cup.

The manual gang control means 8 for the 55 valves 35 includes a lever 41 pivoted on a bracket 42 at the front of the frame, said lever having a handle 43 and being turnably connected medially at 44 to the center of a cross bar 45, as shown by Figs. 1 and 2. At 60 each end of the cross bar 45 there is connected a backwardly extending bar 46, each pivotally connected to a series of upright arms 47, which arms are fixed to corresponding rocker bars 48, having arms 49 fixed 65 thereon and arranged to lift and lower the

valve stems 38 in accordance with the rotation of said bars subject to the hand lever, said bars 48 corresponding with the several rows of gages 4 respectively. The rods 46 enter the manifold 16 at 16' where they fit 70 tightly in the apertured wall 16''.

In order to handle the bottles or other containers 12 expeditiously, the interchangeable boxes 11 are provided therefor adapted for sliding into the machine on the guideways 75 10, said boxes having strong rigid sides and preferably having perforated or screen-like bottoms 11' adapted to permit leakage of any surplus material therethrough into the trough or catch pan 14 having a discharge 80 pipe 14'.

By means of the gang funnels 5 the mouths of the bottles are duly alined and the liquid is directed into the bottles without material waste or spilling. The gang 85 funnel device comprises a plate 5' perforated to aline in registry with the unit gages 4 and provided with downwardly convergent funnel members 50 adapted to fit in the mouths of the bottles respectively. The funnel device 5 is applied to the bottles and the latter thereby accurately alined before the box 11 is inserted into the machine. After filling the bottles the box 11 is removed from the machine and said funnel plate is removed 95 and applied to the next box of empty bottles.

In order that the gang gages 4 may be alined with their brims and with the flush plate 28 on a precisely horizontal level, the frame 1 is made in two parts 1' and 1'', 100 lower and upper respectively, the latter resting adjustably on the former at the corners. Each adjustment bearing (see Fig. 3) comprises a round headed bolt 53, provided with a lock nut 54 and a cup bearing 55 for the 105 bolt head 53'. The shank of bolt 53 is set uprightly in the flange 56 of the lower frame part and the cup 55 is fixed on the under side of the flange 57 of the upper frame part 1''. 110

On account of the more or less viscous and slow running quality of some liquids when cold, especially varnish, and in order to insure prompt filling of the gage cups 4, the latter are inclosed in a steam jacket 9, to which a suitable heating medium may be supplied through the tube 60 and from which said medium may be removed through tube 61. Said jacket 9 is inclosed by the upright frame channels 63, gage plate 28 115 and floor plate 64 through which the downward extremities of the cups 4 project slightly.

The operation of the device is as follows: The filling machine being connected to a 125 tank, reservoir or other source of supply through the feed pipe 2, the operator releases the main gage intake valve 6 by disengaging hook 25 from the float (shown in Fig. 4) which permits the main gage 3 to 130

fill until the supply valve is closed by the rising of the float therein. The operator promptly engages hook 25 with hook 26 and then turns on the valve 7 leading to the unit 5 gages, whereupon the entire contents of the main gage is discharged into the gage manifold 16, whereby the several unit gages 4 are filled, and any remaining surplus is drained into the discharge trough 13, from whence 10 it is returned to the source of supply. The manifold supply valve 7 being closed, the operator then opens the unit discharge valves by pressing inward on the handle 43 of the gang valve mechanism, whereupon 15 the material is discharged downward through the several funnels into the bottles or other containers held in the removable box 11 in the base of the machine. Any surplus material escaping from the gages or 20 bottles either from accident, such as bottle breakage or for any other reason, flows into the catch pan 14 secured to the lowermost part of the machine, from which pan the material collected may be returned either 25 to the source of supply or to a special container for such material in case it has become polluted or otherwise injured.

The operator then closes valve 7 and disengages hook 25, thus opening valve 6 so 30 that the gage 3 may refill. In the meantime, the filled bottles are replaced by empty ones. It is to be noted especially that with this 35 machine the bottling of viscous and air-sensitive liquids can be accomplished very rapidly and without appreciable exposure to the air, which features are extremely desirable in varnish and paint-handling machines.

Referring to the modified form of valve 40 control means shown diagrammatically in Fig. 7, it will be seen that the manifold supply valve controlling the discharge from gage 3 may be controlled simultaneously with and by the same means as the valves 45 35 of the small gages. For this purpose the lever 41 is provided with a link 46 which is connected both to the lever 47 and to a link 66, the latter being in turn connected

to the manifold supply valve 7' provided in the tube 15 leading from the master gage 3. 50 The mechanism is so designed and arranged that when the lever 41 is swung backward toward the right, the main supply valve 7' is closed simultaneously with the opening of the unit gage valves 35. When said lever 55 41 is swung oppositely, that is to the left, the valve 7' is restored to its open position and the valves 35 are closed.

Although but one main embodiment and a slightly modified form of this invention 60 are herein shown and described, it will be understood that numerous details of the constructions shown may be altered or omitted without departing from the spirit of this invention as defined by the following claims.

I claim:

1. A receptacle filling machine, adapted for the rapid handling of liquids of more or less viscous character such as varnishes, 70 paints and the like, comprising in combination a frame, a large master gage, a plurality of relatively small unit gages designed and arranged to serve one for each receptacle to be filled, a broad manifold connecting said master gage and unit gages for transmitting and distributing the successive contents of the former to the latter, the bottom of said manifold being broad and provided with horizontal rows of outlets, 80 and means for controlling the temperature and corresponding fluidity of the liquid as it passes through said machine. 75

2. In a device of the character described, a manifold, including in combination a gage 85 plate disposed horizontally and provided with a plurality of gage cups arranged with their tops fitting in and flush with said plate, and a supply nozzle disposed laterally of said plate and adapted to supply material thereto for filling said cups, said nozzle being fan-shaped and provided with retarding means. 90

Signed at Chicago this 29th day of January, 1919.

AXEL E. SWANSON.
